Whitaker & Prevor

UNITED STATES PATENT OFFICE.

WILLIAM LODOWICK GODFREY, OF BROOKLYN, NEW YORK, ASSIGNOR OF
ONE-HALF TO H. F. HOLLSBERG, OF SAME PLACE.

ELECTRIC DOOR-OPENER.

SPECIFICATION forming part of Letters Patent No. 425,777, dated April 15, 1890.

Application filed September 12, 1889. Serial No. 323,698. (No model.)

To all whom it may concern:

Be it known that I, WILLIAM LODOWICK GODFREY, a citizen of the United States, residing at Brooklyn, in the county of Kings 5 and State of New York, have invented certain new and useful Improvements in Electric Door-Openers; and I do hereby declare the following to be a full, clear, and exact description of the invention, such as will enable 10 others skilled in the art to which it appertains to make and use the same.

My invention relates to improvements in electric door-openers; and it consists in certain improved features of construction and 15 combination of parts, which will be herein-after fully described.

I have illustrated my said invention in the accompanying drawings, and it is fully disclosed in the following specification and 20 claims.

In the drawings, Figure 1 represents a side elevation of my improved door-opener. Fig. 2 is a horizontal section through the same and a portion of a door. Fig. 3 is a detail 25 view showing the parts in their open position.

In the drawings, A represents the frame or casing of the device, which is so constructed as to provide means for attaching and supporting the various parts of the same. The casing A is provided with a face-plate a, which lies flush with the face of the door-jamb when the device is in operative position, and I preferably provide said casing with a web or partition a', which divides the said casing into two parts. In the face-plate a is formed a recess a² to receive the bolt of the latch on the door, and within the casing is pivoted a tumbler B, which is provided with a notch or 35 recess b, forming a continuation of the bolt-recess a², and providing a shoulder b', which normally engages the straight side of the latch-bolt and prevents the opening of the door. The opposite side of the shoulder b' is 40 inclined to engage the inclined face of the latch-bolt and force it inward against its spring as the door is closed. The tumbler B is provided with a suitable spring b², which holds it normally in position to be engaged 45 by a latch-bolt. The tumbler B is provided at each end with arms b³ b³, which extend rearwardly a short distance in an inclined di-

rection from the point of pivoting and are connected by a cross-bar b⁴.

At the rear of the tumbler B is a cam C, 55 which is pivoted between two lugs projecting from the main casing A, and consists of a lever having a long arm c and a short arm c', which extend at an angle to each other from the point of pivoting, and the arm c is preferably curved, and is provided adjacent to its free end with a curved bearing portion c². The cross-bar b⁴ of the tumbler B rests normally in the angle formed by the arms c and c' of the cam C, and when in that position the free end of arm c will be adjacent to the said tumbler at its point of pivoting. The said arms c and c' are so constructed that a movement of the tumbler B in one direction will cause the cross-bar to bear upon 65 the under side of the curved arm c and raise the same, while a movement in the opposite direction will cause said cross-bar to engage the short arm c' and force it in the opposite direction, returning the arm c' to its normal 70 position. Thus it will be seen that the cross-bar of the tumbler operates the cam C positively in both directions.

Adjacent to the free end of the arm c of the cam C is pivoted a lever D, which serves as a 80 keeper or locking-lever. This lever is provided with a suitable spring d, which holds it down in contact with the arm c of the cam. If, however, the said arm is raised, as before described, the curved bearing-surface c² will 85 bear against the under side of the keeper D and raise it. It will be noticed that the cross-bar b⁴ of the tumbler bears against lever-arm c adjacent to its pivot, and that the curved portion c² of said arm bears against the keeper D adjacent to its point of pivoting. It will 90 therefore be apparent that a very slight detent applied to the free end of the keeper D will, by means of the great leverage given by both levers D and c, be able to resist a much 95 greater force applied to the shoulder b', as in an effort to force open the door.

In order to provide means for holding the free end of the keeper D, I employ an oscillating locking device, which consists of a spindle E, provided with a projection e to engage the end of the keeper D and hold it from being forced backward. The spindle is also provided with a pin or projection e', which en-

gages suitable stationary lugs or projections f , and thereby limits the oscillation of the spindle in both directions. A spring e^2 holds the pin e' in engagement with one of said lugs 5 and the projection e in position to lock the keeper D from movement. In constructing this oscillating device I prefer to mount the spindle E in suitable ears or supports F , which are secured to the casing A , and secure said 10 spindles in position to rotate by means of screws passing through said ears and entering apertures in the ends of the spindle.

The free end of the keeper D is provided on its forward face with an inclined portion d' , 15 as shown, so that when thrown back into its normal position by its retracting-spring d it will force the locking projection e to one side and resume its locked position.

To some convenient portion of the casing 20 A is secured an electro-magnet G , adapted to act upon an armature g , which is provided with a suitable retracting-spring g' . To the said armature g is secured an arm b^2 , which engages a projection e^3 from the spindle E 25 when the armature is drawn to its magnet and oscillates the said spindle, thereby removing the locking projection from engagement with the keeper D . If the door is pulled with some degree of force while the keeper is thus 30 free, the latch-bolt will force back the tumbler B , raising the arm c of the cam and the keeper D , as shown in Fig. 3, and releasing the said latch-bolt, whereupon the door may be opened. As soon as the circuit through magnet G is 35 broken, the armature and the spindle E return to their normal positions under the influence of their springs, and the projection e is again in the path of the keeper D .

When the latch-lock is disengaged from the 40 tumbler by the opening of the door, as before described, the tumbler is returned to its normal position, and in so doing the cross-bar b^4 strikes the short arm c' of the cam, returning said cam positively to its position and permitting the keeper D to pass the locking 45 projection e , and the parts are again in their normal positions. Should the tumbler and connected parts return to their normal positions before the locking-spindle is released by the 50 armature-lever, when said spindle is released the projection e will return to its position in rear of the keeper D .

The arrangement of the parts is such that no pressure will be exerted upon the detent 55 or projection e by an ordinary pull upon the door; but when a considerable pull is exerted the keeper D will be held from all movement by the detent e .

It will be understood that the electro-magnet G may be operated and controlled from 60 any suitable point at any desired distance, as found most convenient and desirable.

I do not wish to be limited to the exact details of construction herein shown and described, as the same may be varied without departing from the spirit of my invention. 65

What I claim, and desire to secure by Letters Patent, is—

1. In a door-opener, the combination, with a tumbler, the keeper, the locking device for 70 said keeper, and means for releasing the same, of a cam interposed between said tumbler and keeper and adapted to be moved positively in both directions by said tumbler, substantially as described. 75

2. In a door-opener, the combination, with a tumbler provided with a cross-bar, of a cam having arms adapted to be engaged by said cross-bar for moving the same positively in both directions, a keeper for said cam, an oscillating locking device for said keeper, and a tripping device for oscillating said locking device and releasing said keeper, substantially as described. 80

3. In a door-opener, the combination, with the tumbler provided with a cross-bar, of a cam provided with a long arm and a short arm disposed at an angle thereto, both of said arms adapted to be engaged by said cross-bar for moving said cam positively in both directions, 85 a keeper for said cam, and means for locking and releasing said keeper, substantially as described. 90

4. In a door-opener, the combination, with the tumbler provided with a cross-bar, of a 95 pivoted cam having a long arm and a short arm disposed at an angle to each other and adapted to be engaged by said cross-bar for moving said cam positively in both directions, a keeper engaging the long arm of said 100 cam and pivoted adjacent to the free end of the same, an oscillating spindle having a projection in the path of said keeper, and an electro-magnet provided with an armature-lever adapted to oscillate said spindle, substantially as described. 105

5. In a door-opener, the combination, with the tumbler, the cam operated thereby, and the keeper engaged by said cam, of an oscillating spindle provided with a projection in 110 the path of said keeper and a projection adapted to be engaged by an armature-lever, an electro-magnet for operating said armature-lever, and a retraction-spring for retracting said spindle after it has been rotated by 115 said armature-lever, substantially as described.

In testimony whereof I affix my signature in presence of two witnesses.

WILLIAM LODOWICK GODFREY.
